DESIGN FOR A CIGAR AND CIGARETTE REST FOR ASH TRAYS

Edward F. McDonald, Buffalo, N. Y.

Application October 15, 1942, Serial No. 108,531

Term of patent 14 years

(Cl. D85—2)

To all whom it may concern:

Be it known that I, Edward F. McDonald, a citizen of the United States, residing at Buffalo, in the county of Erie and State of New York, have invented a new, original, and ornamental Design for Cigar and Cigarette Rest for Ash Trays, of which the following is a specification, reference being had to the accompanying drawing, forming part thereof.

In the drawing:

Fig. 1 is a side elevational view of a cigar and cigarette rest for ashtrays, showing my new design,

Fig. 2 is a front elevational view,

Fig. 3 is a plan view, and

Fig. 4 is a rear elevational view thereof.

I claim:

The ornamental design for a cigar and cigarette rest for ash trays, as shown.

EDWARD F. McDONALD.
